UNITED STATES PATENT OFFICE

BRADFORD T. BORDEN, OF LAKEWOOD, OHIO, ASSIGNOR, BY DIRECT AND MESNE ASSIGNMENTS, TO THE BORDEN COMPANY, OF WARREN, OHIO, A CORPORATION OF OHIO

DIESTOCK

Application filed June 27, 1929. Serial No. 374,160.

My invention relates to improvements in die stocks, and particularly to those of the leader screw type.

Briefly stated,—the invention has for its primary object the provision in a die stock, as characterized, of means whereby the dies may be adjusted or removed regardless of the relative position of the leader screw and its nut formed in the work holder and without necessitating the unscrewing or separating of the leader screw from the work holder.

The invention also contemplates a die stock, as characterized, which is simple in construction, inexpensive of manufacture, and highly efficient in practical use,—the invention also residing in certain novel features of construction, combination, and arrangement of the various parts all of which will be readily understood and appreciated by those skilled in the art upon reference to the accompanying drawings in connection with the following detailed description.

It is to be understood that the drawings illustrate what is now regarded as being a preferred embodiment of the invention, although same is susceptible of other mechanical expressions within the spirit and scope of the subject matter claimed hereinafter.

In the drawings,

Figure 1 is a top plan view of a die stock incorporating my invention;

Figure 2 is a sectional view on the line 2—2 of Figure 1;

Figure 3 is a perspective view of the post-carrying ring or annulus and associated latch element;

Figure 4 is a sectional view taken on the line 4—4 of Figure 2;

Figure 5 is a detailed sectional view taken on the line 5—5 of Figure 4;

Figure 6 is a detailed sectional view taken on the line 6—6 of Figure 1, and

Figure 7 is a detailed perspective view of one of the segments or dies.

Referring specifically to the drawings wherein the same reference characters have been used to designate the same parts throughout,—numeral 1 denotes a work holder of tubular form and which comprehends a

number of work engaging elements 2, which are preferably of the type illustrated.

The work holder has the usual tubular neck 3 and shoulder 3^a, which supports the annulus or ring 4 having sockets 5 which carry the upstanding posts 6.

The posts 6 have a flat face 6^a from which projects a diagonal rib 7. This rib is adapted to engage in any one of a plurality of transverse grooves 7^a formed in opposite sides of the dies 7^b which are received in radial slideways 8 in the die frame 9,—it being understood that this die frame 9 has a number of holes 10 receiving the posts and which holes communicate with the slideways so that the post ribs may engage the grooves 7^a of the dies.

The die frame has the usual tubular leader screw 15 through which the work extends and which screw is received in the tapped central hole or recess of the work holder.

The die frame has a pair of handle sockets 17 for the reception of handles 18 whereby the frame along with the post-carrying ring may be rotated about the work holder,—the die frame 9 being actuated in the direction of the work holder through the medium of the leader screw and its threaded connection with the work holder and likewise by reason of the engagement of the dies with the work.

Ordinarily, in a tool of this type, it is necessary in order to remove the dies for grinding or to secure new adjustments to unscrew the die frame, or rather turn the die frame so as to separate the leader screw from the work holder so that the posts 6 will be removed entirely from the post holes of the die stock to free the ribs 7 from the grooves in the dies.

However, in this tool I provide the post-carrying ring with a plate 20 pivoted as at 21 to the upper face by means of the screw shown,—the plate 20 having an arcual portion 20^a projecting beyond the inner periphery of the post-carrying ring to engage the surface groove 23 adjacent the top of the neck 3. Thus, when plate portion 20^a is in engagement with the top surface groove 23 of work holder 1 the post-carrying ring 4 is rotatably held against shoulder 3^a. When

the plate 20 is swung outwardly ring 4 may be moved upwardly to free post ribs 7 from the dies, it being observed that the ribs 7 terminate a considerable distance short of the ring-carried ends of the posts. The plate 20 is normally held in operative position by means of a latch member 26 working through plate 20 and adapted to seat in a hole 26^a in the post-carrying ring. Plate 20 has a boss 27 in which latch 26 works, there being a latch actuating coil spring 28 normally pressing the latch outwardly, the spring being confined in place by a screw 29 in the end of the boss. It will be perfectly obvious that the plate 20 can be swung laterally so that its arcual portion 20^a will be clear of the work holder groove 23 so that the post-supporting ring 4, along with the plate 20, can be moved upwardly to withdraw the ribs 7 of the posts 6 entirely out of the grooves 7^a of the dies 7^b so that same can be pulled out of their guideways in the die carrier or adjusted so as to present different die grooves to the ribs.

If desired, an adjustable stop may be provided to prevent the unpremeditated freeing of the dies even though the post ring be unlatched from the work holder. Such a stop is illustrated by the screw 30 in Fig. 6. This screw is idle in the normal operation of the die stock, but if it stands turned in to the limit as shown in this figure, the post ring 4, if released and brought toward the die carrying frame, will abut this screw before the ribs 7 clear the dies, so that under these conditions, the dies are not released. One or more rotations of the screw outwardly will allow the ring to approach close enough to the die carrying frame to release the dies.

The taper of ribs 7 is about $\frac{3}{4}$. This, of course, can be varied. The tool is much lighter than others in its class and is very advantageous in that it involves no cam to turn or get gummed up,—it being noted that each segment gets its taper from a separate post 6. In a cam tool where one segment or die is a trifle longer than the others the operation of the whole assemblage is prevented,—a thing which is not the case with my tool. Furthermore, it will be noted that the boss 27 of the plate or latch element 20 serves as a stop or abutment to limit the approach of the die frame toward annulus 4.

Having thus described my invention, what I claim and desire to secure by Letters Patent is:

1. A device of the class described comprising a die-carrying frame, dies removably supported therein, controlling means for said dies adapted to be disengaged from the dies in a certain position of the controlling means, a support for said controlling means, a body with respect to which said support is axially movable into position to release the dies, and a finger operated latch carried by said support and engageable with said body to pre-

vent axial movement of the support with respect to said body.

2. A die stock comprising a die frame, dies movably carried by said frame, controlling means for said dies adapted to be disengaged from the dies in a certain position of the controlling means, a support for said controlling means, a work holder, said support being movable about said work holder and also movable axially toward the die frame into position to release the dies and latch means carried by said support and positionable to engage said work holder to prevent movement of the support in the direction of the length of the work.

3. In a die stock having a work holder, an axially movable die-carrying frame having dies, and an actuating member for controlling the dies adapted to be disengaged from the dies in a certain position of the controlling means, a latch pivotally carried by said die actuating member and movable to engage a portion of said work holder whereby to prevent movement of the actuating member axially of the work into position to release the dies.

4. The combination in a leader screw die stock having a work holder, a member rotatably mounted thereon and provided with die actuating means releasable from the dies without disconnecting the leader screw couple; of a latch element associated with said work holder and member and operable to prevent movement of the latter in a direction to free the dies.

5. The combination in a leader screw die stock having a work holder, a member rotatably mounted thereon and provided with die actuating means releasable from the dies when the member is immediately adjacent the die holder; of a finger operated latch pivoted on the member and adapted to engage said work holder and operable to prevent independent movement of the member in a direction to actuate the dies away from the work.

6. In a die stock having a positive leader screw feed or the like and including a die carrier, a work holder and a post-carrying frame rotatable thereabout, the post having die engaging ribs tapered to control movements of the dies as the die carrier moves relatively to said frame, said ribs terminating a sufficient distance from the post-carrying frame to clear the dies when the frame is positioned close to the die carrier, in combination with a latch member associated with the work holder and post-carrying frame for holding the same against relative axial movement.

7. In a die stock having a positive leader screw feed or the like and including a die carrier, a work holder and a post-carrying frame rotatable thereabout, the posts having die engaging ribs tapered to control movements of the dies as the die carrier moves relatively of said frame; the combination of a latch

member associated with the work holder and post-carrying frame for holding the same against relative axial movement but allowing such movement when desired, and said post 5 ribs terminating short of the inner ends of said post a distance approximating the thickness of the dies whereby when the frame is elevated against the die carrying frame the ribs will be freed of the dies to permit 10 adjustment or removal thereof.

8. In a die stock having a die carrier, a work holder and a post-carrying frame rotatable thereabout, the posts having die engaging ribs tapered to control movements of the 15 dies as the die carrier moves relatively of said frame, in combination with a latch member associated with the work holder and post-carrying frame for holding the same against relative axial movement but allowing such 20 movement when desired, and said post ribs terminating short of the inner ends of said posts a distance approximating the thickness of the dies whereby when the post-carrying frame is elevated against the die-carrying 25 frame the ribs will be freed of the dies to permit adjustment or removal thereof, and a stop element associated with the die-carrying frame and post-carrying frame and being positionable to limit approach of the same to 30 toward one another whereby to prevent the freeing of the ribs from the die except when desired.

9. In a die stock having a work holder and a die-carrying frame and means for effecting 35 a positive feeding of the die-carrying frame toward the work holder in the thread cutting operation, the combination of die controlling means movable relatively of the die-carrying frame, said die-controlling means having omitted 40 portions positionable to permit removal of the dies, and latch means associated with said die controlling means for preventing or allowing movement of the same to put said omitted portions in effective position.

45 10. In a die stock having a work holder and a die-carrying frame for effecting a positive feeding of the die-carrying frame toward the work holder in the thread cutting operation, the combination of die controlling means 50 movable relatively of the die-carrying frame, said die controlling means having omitted portions positionable to permit removal of the dies, and a finger latch movably mounted on said die-controlling means and engageable at 55 will with an annular groove in said work holder for normally preventing movement of the same to put said omitted portions in registration with the dies.

60 11. In a die stock the combination of a die carrying frame, a work holder, a ring having posts for controlling the recession of dies in the die carrying frame and a latch lever pivoted to the ring and having an inner face 65 adapted to occupy an annular groove in the work holder or clear the same, said latch lever

having an upstanding boss which forms a handle for the latch, and a detent mounted in the boss and comprising a slidable member adapted to engage a depression in the ring and a spring pressing said member downwardly and an anchorage for the spring.

70 12. In a die stock, the combination of a die carrying frame, dies removably supported thereon, controlling means for said dies comprising a rotatable ring with posts having inclined ribs, said ribs being omitted for a portion of the length of the posts adjacent the ring whereby, when the ring is shifted toward the die-carrying frame into a certain position, the dies are freed to move in or out.

75 13. In a die stock, the combination of a die-carrying frame, dies removably supported thereon, a work holder, a ring revoluble on the work holder, pins carried by the ring, inclined ribs on the pins, said ribs terminating short of the base of the pins, whereby, when the ring is close to the die carrier frame, the chasers are freed for movement in or out, and a lead screw connecting the die-carrying frame with the work holder.

80 14. In a die stock, the combination of a die carrying frame, dies slidably mounted therein and each provided with a plurality of notches located respectively different distances from the active end of the die, a revoluble ring, posts carried thereby, ribs on the posts each adapted to occupy either of the notches in a corresponding chaser, said ribs terminating short of the full length of the posts so that in a certain position of the ring without disassembling the die stock the chasers are freed from the posts and may be moved in or out.

85 15. In a die stock, the combination of a die carrying frame, dies slidably mounted therein and each provided with a plurality of notches located respectively different distances from the active end of the die, a work holder adapted to be clamped to the work, a lead screw connecting the work holder with the die-carrying frame, a ring rotatably mounted on the work holder but adapted to be freed therefrom for longitudinal movement toward the die-carrying frame, a latch adapted to connect the ring with the work holder, posts carried by said ring, and ribs on the posts each adapted to occupy either of the notches in a corresponding chaser, said ribs terminating a sufficient distance short of the ring so that in a certain position of the ring the chasers are freed from the posts and may be moved in or out.

90 16. In a die stock, the combination of a chaser-carrying frame, a work holder, a lead screw couple connected to the chaser frame and work holder respectively, a revoluble ring, posts carried thereby adapted to contact with the chasers to control recession thereof, a latch for coupling the ring to the work holder, and means whereby a certain posi-

tion of the ring when released from the work holder may free the chasers while the work holder and chaser frame are connected by their lead screw.

17. In a die stock, the combination of a chaser-carrying frame, a work holder, a lead screw connecting the two, a ring normally adapted to be revolvably mounted on the work holder, said ring carrying posts having ribs 10 adapted to engage notches in the chasers, said ribs terminating short of the ring whereby when the ring is adjacent the chasers the ribs will clear the same, and means for latching the ring to the chaser frame in a manner 15 to limit the longitudinal movement of the ring without interfering with the rotary movement.

18. In a die stock, in combination of a die carrying frame, a work holder, a ring having 20 posts for controlling the recession of dies in the die carrying frame, there being one position of the posts where the dies are free, and a latch lever pivoted to the ring and having an arcuate inner face adapted to occupy 25 an annular groove in the work holder or clear the same, whereby the ring may move the posts to releasing position.

In testimony whereof I affix my signature.
BRADFORD T. BORDEN.
